UNITED STATES PATENT OFFICE.

DANIEL J. MURNANE, OF CHICAGO HEIGHTS, ILLINOIS, ASSIGNOR TO ZOURI DRAWN METALS COMPANY, OF CHICAGO HEIGHTS, ILLINOIS, A CORPORATION OF ILLINOIS.

GLASS-SECURING DEVICE.

1,351,058.

Specification of Letters Patent. Patented Aug. 31, 1920.

Application filed July 30, 1917. Serial No. 183,487.

To all whom it may concern:

Be it known that I, DANIEL J. MURNANE, a citizen of the United States, residing at Chicago Heights, in the county of Cook and 5 State of Illinois, have invented new and useful Improvements in Glass-Securing Devices, of which the following is a full, clear, concise, and exact description, reference being had to the accompanying drawing, forming 10 a part of this specification.

My invention relates to glass securing devices, and more particularly to settings for plate glass such as are commonly used in store fronts.

15 One of the objects of my invention is to provide an improved skeleton sash or setting for the glass to take the place of the usual solid bronze or metal sash or setting but which will look like such a solid sash and 20 present an appearance equally as good, and be as durable and lasting in use, besides having the advantage of drainage, if desired, to take care of the water of condensation. Additional advantages and objects are ex- 25 treme simplicity and cheapness of manufac- ture, ease of installation, and the use of a minimum amount of material while at the same time affording a safe, solid and rigid support for the glass. A further object is 30 to provide a setting of this class in which the depth of the rabbet is greater than is ordinarily possible in settings of this class, thus permitting the glass-supporting mem- bers to engage the glass at a greater distance 35 from the edge of the plate and thereby af- fording a better and more secure support for the glass. Still another object is to pro- vide a construction in which there can be no undue pressure on the glass adjacent the 40 securing screws or elsewhere, in which there is no pinching of the glass or strain due to direct screw pressure at the holding screw points, whereby liability to breakage is avoided, and which may be installed by any 45 competent glazier without special skill, training or care, and without breakage of the glass.

In the drawings, in which I have shown one form of my invention—

50 Figure 1 is a perspective view showing the lower edge of the plate glass, the window-sill, and the setting for the plate glass;

Fig. 2 is a plan view of the same;

Fig. 3 is a cross-section on the line 3—3 55 of Fig. 2;

Fig. 4 is a perspective view of one of the rigid supports of the outer member; and

Fig. 5 is a similar view of one of the supporting brackets of the inner member.

Referring to the drawing in detail, the 60 setting shown comprises the inner supporting member 10, secured to the riser 11 for supporting the inner side of the plate glass 12, and the outer supporting member, molding or stop 13 secured to the sill 14 and supporting the outer side of the plate glass 12. 65

The inner member 10 comprises a thin sheet metal channel member 15 extending throughout the length of the edge of the glass, and a plurality of supporting brackets 70 16 housed by the channel member and placed therein at frequent intervals, say, every ten inches, and supporting and reinforcing it against pressure from the plate glass. The brackets 16 may be secured in the channel 75 member 15 in any suitable manner, as by striking projections 17 from the channel member 15 into the ends of the tubular portions 18 of the bracket 16. The tubular portions are of such length as to completely 80 span the space across between the edge flanges of the channel 16, and the punched-in portions 17 grip the edges of the tubular portions 18, thereby preventing displacement of the brackets themselves and in turn 85 preventing the said flanges from loosening and springing away from the ends of the tubular portions. The whole forms a rigid inner support for the glass plate.

The outer supporting member or stop 13 90 is of skeleton construction and comprises the sheet metal channel member 20, forming a molding, and a plurality of supports 21 housed by the channel member and placed at frequent intervals, say, every ten inches, 95 throughout its length, for supporting it in an upright position like a solid stop and for sustaining and reinforcing the channel member not only against the pressure of the screws 22, which secure the clamping means 100 to the sill 14, but also to make it a solid and rigid support for the glass.

The channel member 20 has an inwardly extending flange 23, bearing on the sill 14, on which one leg 24 of the support 21 bears, 105 and also has a downwardly extending flange 25 for engaging the plate glass 12, the support 21 being sprung into position in the channel and held in place between the flanges 23 and 25 (Figs. 1 and 3). 110

The support 21 is positioned and retained lengthwise within the channel member 20 by means of a countersunk portion 26 on the channel member, which is pressed into the opening 27 of the support 21 after it is in position. This countersunk portion 26 is shaped to receive the conical head of the screw 22.

The support 21 is provided with a downwardly extending leg 29 which bears on the sill 14, thus holding the channel in upright position on the sill or frame. The bearing portion 30 of the support 21 adjacent the countersunk portion 26 of the channel member 20 firmly supports and sustains the channel member against buckling due to the pressure of the screw 22, and the legs 24 and 29 limit the distance to which the screw can be driven into the sill.

The support 21 is preferably formed and stamped of a single piece of sheet metal which may be so stamped as to provide stiffening webs 31 to prevent collapse of the support under the pressure of the screw.

The sill 14 is covered with a sheet metal molding 32 extending down over the front edge of the sill and back under the glass and upwardly along the riser to the point 33, slightly beneath the lower edge of the flange of the inner channel member. This sill covering is provided with slots 28 to receive the screws 22, formed by punching up the metal to form the flanges 34, the slots affording room for adjustment in position, both laterally and longitudinally, of the screws 22, and therefore the outer member 13, to accommodate different thicknesses of glass or a different endwise position, and the flanges 34 preventing the entrance of drainage water into said slots.

Drainage of the water of condensation from the inside of the glass, if desired, and also ventilation to the extent permitted by the drainage apertures, may be provided by the holes or slots 35, in any desired number, formed in the outer edge wall of the member 13, and the corresponding holes or slots 36 formed in the horizontal web of the inner channel member 10.

The same, or a similar construction, can be used for the side and top edges of the plate glass, except that in such cases the sill covering 32 would ordinarily not be employed, the screws 22 for the side and top setting being screwed into the window frame.

In use, the inner member 10 is secured to the riser 11, or other suitable portion of the window frame, by means of the nails or screws 39, and the plate glass 12 is set up against the inner clamping member, its lower edge resting on two setting blocks, one near each vertical edge, as is common. Owing to the fact that there are no screws or other clamping parts of the structure between the

edge of the glass and the sill covering, these setting blocks may be low or thin, and ordinarily are just a piece of heavy or sole leather 41. The outer member 13 is then set on the sill and pushed up by the hand 70 against the plate glass 12 and the screws 22 are inserted through the openings 26 in the channel member 20 and the slots in the sill covering and screwed into the sill 14 or other suitable portion of the window frame. 75 The supports 21 serve to support the stop 20 in upright position on the sill or frame both before being moved into position or fastened, as well as after, similar to an ordinary solid stop or quarter-round, and to support the outer face of the glass, and they take practically all of the strain due to the screws 22, thus preventing buckling or deformation of the channel 20. Any ordinary glazier can do this without special skill or 80 experience with the particular setting because it is merely necessary to bring the stop up closely to the glass and drive the screws home. There is no danger of pinching the glass by tightening these screws, as might 85 be the case if the screws extended horizontally past the edge of the glass into the back riser and thus by direct screw pressure put a strain on the glass at these screw points of contact.

Although the leg 24 bears directly on the flange 23, it also bears indirectly on the sill 14, the pressure being transmitted through the flange 23. The drawn sheet copper of which the outer molding 13 or 100 channel 20 is preferably made can thus be of light gage material, due to the presence of the rigid supports 21, and forms as a whole a strong, rigid support, molding or stop for the outer side of the glass. The same is 105 true of the inner member. A saving of sheet material in the outer stop is effected also, because of the slight depth of flanges 23 and 25 required, and also the comparatively low height of the setting from the sill or jamb, 110 due to the absence of all screws or other clamping mechanism between the edge of the glass and sill. The inner member 10 is also preferably made of drawn sheet copper, which is particularly desirable in glass settings because of its lasting quality and its 115 inherent smoothness and softness as a grip for the glass. It may, however, be of wood or any other desired type of construction.

Various modifications and changes may be 120 made without departing from the invention as set forth in the appended claims.

Having thus described my invention, what I claim as new and desire to secure by Letters Patent is—

1. In a window glass setting, a stop for one side edge of the glass constructed to be secured to the face of the sill or frame which is adjacent to the edge of the glass and substantially perpendicular to the plane there-

of, said stop comprising a thin sheet metal channel strip forming a molding, supports placed at frequent intervals within said molding to sustain the same in upright position on the sill or frame, and having a bearing portion in contact with the wall of the molding to support the same against pressure toward the sill or frame, and securing means passing through said molding 10 and supports and into the sill or frame.

2. In a window glass setting, a stop comprising a thin sheet metal channel strip forming a molding, supports placed at frequent intervals within said molding and resting on the sill or frame to sustain the molding in upright position on the sill or frame, said supports having a bearing portion in contact with the wall of the molding opposite the sill or frame to support the same against pressure, said bearing portion having an opening and the adjacent wall of said channel being depressed into said opening to position the support in the strip, and securing means passing through said molding and supports and into the sill or frame. 25

3. In a window glass setting, a stop comprising a thin sheet metal channel strip forming a molding, supports placed at frequent intervals within said molding and bearing on the sill or frame to hold the stop in upright position, said supports having a bearing portion in contact with the wall of the molding to sustain the same against screw pressure, said bearing portion having 30 a screw opening therein and the adjacent wall of said channel being countersunk into said opening to position the support in the strip and to receive the head of the screw or nail, and securing screws passing through 35 said molding and supports and into the sill or frame. 40

4. In a window glass setting, a stop comprising a thin sheet metal channel strip forming a molding, said molding having a flange along one edge to rest against the glass and a flange at the opposite edge to 45 rest on the sill or frame, supports placed at frequent intervals within said molding to hold the same in upright position on the sill or frame, said supports fitting in closely between the said two edge flanges of the strip with their bearing portions supporting the outer wall of the molding, and means passing 50 through said molding and the supports 55 and into the sill or frame to secure the stop in position.

5. In a window glass setting, a stop comprising a thin sheet metal channel strip forming a molding, supports placed at frequent intervals throughout the length of 60 said strip, said supports being stamped from sheet metal and each having two legs and a bearing portion with strengthening webs therebetween, the said legs bearing on the sill or frame to hold the strip in 65 upright position and the bearing portion against the wall of the strip to support the same against pressure, and means driven through the said wall of the molding and bearing portions of the supports and into 70 the sill or frame to secure the stop in position.

6. In a window glass setting, a stop comprising a thin sheet metal channel strip forming a molding and having two edge 75 flanges, one bearing against the glass and the other against the sill or frame, supports placed at intervals throughout the length of said strip and each having a leg bearing on said sill or frame flange of the strip 80 and another leg bearing on the sill or frame itself, said supports also engaging the flange of the strip next the glass and having a bearing portion supporting the intermediate wall of the strip, and securing means passing 85 through the strip and the said bearing portion of the supports and driven into the sill or frame.

7. In a window glass setting, a support for the glass, a sheet metal sill covering, 90 securing means for said support passing through openings in said sill covering and into the sill, and an upstanding wall or flange surrounding said openings in the sill covering to prevent the entrance of drain- 95 age water.

8. In a window glass setting, a support for the glass, a sheet metal sill covering, securing means for said support passing through openings in said sill covering and into the sill, said openings being in the form of slots wider than the dimensions of the said securing means to afford limited adjustment in position of said support and securing means both longitudinally and laterally 100 on said sill covering and having their edge walls punched up to prevent the entrance of drainage water.

In witness whereof, I have hereunto subscribed my name.

DANIEL J. MURNANE.
